UNITED STATES PATENT OFFICE.

JOHN GEORGE LEYNER, DECEASED, LATE OF LITTLETON, COLORADO, BY LINA M. LEYNER, ADMINISTRATRIX, OF LITTLETON, COLORADO, ASSIGNOR TO THE LEYNER TRACTOR AND MANUFACTURING COMPANY, OF DENVER, COLORADO, A CORPORATION OF COLORADO.

DRIVING MECHANISM FOR THE GROUND-TREADING MEMBERS OF TRACTION ENGINES.

1,424,494.

Specification of Letters Patent. Patented Aug. 1, 1922.

Application filed November 11, 1920. Serial No. 423,437.

To all whom it may concern:

Be it known that JOHN GEORGE LEYNER, deceased, late a citizen of the United States of America, and resident of Littleton, county of Arapahoe, and State of Colorado, did invent a new and useful Driving Mechanism for the Ground-Treading Members of Traction Engines, of which the following is a specification.

10 The invention relates to improvements in driving mechanism for the ground treading members of traction engines.

And the objects of the invention are:

First: To provide a driving mechanism for 15 traction engines that will rotatively drive the endless ground treading tracks, or the round traction wheels of traction engines, over fields, roads or hill sides in either forward or backward, or in turning directions.

20 Second: To provide a driving mechanism for traction engines that is strongly supported and enclosed in substantially dust proof housing casings.

Third: To provide a driving mechanism 25 for traction engines that consists of few parts and is simple in construction and that transmits and applies power directly to the endless ground treading track's operating members.

30 These objects are attained by the mechanism illustrated in the accompanying drawings, in which:

Figure 1 is a transverse, sectional view through a tractor, showing the improved 35 driving mechanism for operating the sprocket-carrying shaft which operates the endless traction chain.

Fig. 2 is a side view, partly in section, of 40 a modified form of the driving mechanism, and

Fig. 3 is a sectional view of Figure 2, on the line 3—3.

Similar letters of reference refer to similar parts throughout the several views.

45 Referring to the drawings:

The Figures 1, 2 and 3, designate a driving mechanism for traction engines embodying the invention.

In these views and also in all of the details 50 where it is shown, the numeral 1 designates a vertically positioned power operated and power driven driving shaft; the upper end

of this vertical shaft has mounted on and keyed or otherwise secured to it, a sleeve 2, that is provided with a projecting flange 3, the terminal end of which is provided with a vertically extending annular flange 4, and a laterally projecting annular flange 5, and to the lateral flange 5, is removably secured a worm gear 6, preferably by bolts 7. The invention, however, contemplates any means for securing this worm gear to the sleeve 2, or, if desired, directly to the vertical shaft; as, if desired, the sleeve 2, can be dispensed with. As used, it acts as a hub member for the worm gear to which the rim and tooth portion of the worm gear is detachably secured, in order that a worn out worm gear ring can be replaced by a new one without removing the hub or sleeve 70 member 2, from the shaft.

This worm gear 6, meshes with a worm pinion 8, that is keyed or otherwise secured to a shaft 9, that extends adjacent to and is rotated by the engine or motor, which is preferably a gasoline operated motor, but may be a steam operated engine or any other power developing and transmitting medium that can be connected to this shaft 9, to rotatably drive it. 80

The upper terminal end of this vertical shaft is preferably journaled in rolling bearings, although any suitable form or kind of a journal bearing may be used, as desired. There is illustrated, however, a ball bearing 10, which consists of a raceway collar 11, that is secured to the shaft 1, preferably to a reduced portion 1^a, of the shaft. This collar is provided with a raceway member 1^b, in which a circumferential row of 85 steel balls 1^c is mounted, which are held in place by a surrounding concentric collar 12, in which there is also a raceway into which the balls fit. This collar 12, is seated and secured in a cup-shaped recess 13, 95 that is formed in the center of a plate 14, that forms the top of the housing members of the driving mechanism.

The outer ends of this plate 14, are secured to the ends of a housing casting 15, 100 by bolts 16. This housing has a curved side portion on that side of it that encloses the worm pinion, that is formed concentric with it, and encases it at a short distance from it,

while the opposite side of this housing member encloses the adjacent edge of the worm gear.

This housing member 15, is provided with 5 two lower end portions 17 and 18, that extend downward from a horizontal portion 19, that extends from the opposite sides of this housing casting towards the vertical shaft and terminates in a vertical hub portion 20, that surrounds the shaft 1, and also the sleeve 2, and its lower end supports a journal bearing in which the lower end of the shaft 1, is rotatably mounted. There is preferably illustrated a rolling bearing 22, 15 in the lower end of this hub 20, which is formed of the collar 23, that is secured to the shaft, and a collar 24, that is secured in the lower end of the hub, and a plurality of tapering rollers 25, that are rotatably mounted 20 ed between these two collars.

The extreme lower end portion of the vertical shaft is provided with a bevel gear pinion 26, that is keyed or otherwise secured to it. The end of the shaft extends 25 through the gear pinion and is threaded. A thread locking collar 27, is illustrated on the lower threaded end of the vertical shaft below the bevel pinion. The shaft also extends through a ball bearing at the upper 30 end of the vertical shaft, far enough to be threaded and to receive a thread locking collar 27^A, which is turned down against the upper end of the sleeve 11. If desired, however, a nut, either with or without a nut 35 locking device, may be used instead of the collars on the opposite ends of the vertical shaft 1.

Centrally below the vertical shaft 1, is positioned a shaft 28, which is journaled in 40 any suitable bearings. For the sake of illustration are indicated, however, rolling bearings 29, which are placed at a short distance from its opposite end portions, and at an equal distance from the center of its 45 length. These rolling bearings consist of a collar 30, surrounding and secured to the shaft 28, and a concentrically arranged and surrounding collar 31, between which and the shaft collar, the rolling members 32, 50 are operatively mounted.

The shaft 28, is positioned at right angles to the vertical shaft 1 and in a horizontal plane.

A bevel gear 33, is mounted on and secured to the shaft 28, and it meshes with the bevel pinion 26, on the lower end of the vertical shaft 1.

The rolling bearings 32, are placed in the hubs 34, of a supporting and housing casting 35. The hubs 34, are provided with an internal bore 36, that terminates in a shoulder 37, against which the outer collar 31, is turned, while it is fitted tightly in the bore 36, of the hubs. The shoulders in the 65 hubs of the castings 35, form abutments that

prevent the bearings from moving inwardly towards the center of the length of the shaft, and they are prevented from moving towards the opposite ends of the shaft by 70 thread locking collars, that are threaded to a threaded portion 38, that is formed on the shaft at the outer end of the rolling bearing shaft collar 30, and is arranged so that the thread locking collars are turned up against the shaft collars of the rolling bearings. 75

This housing 35, is also provided with an upwardly projecting hub 39, that surrounds and fits the lower portion of the hub 20. This hub portion is also surrounded by angle plates 40, that surround and fit 80 it closely, and that are provided with a top flange portion 41, that is secured by the bolts 42, which also extend through a plate 43, that is termed the crown plate, and which forms the top member of the outside guard 85 housing plates 44 and 45. The object of these outside guard housing plates will be presently described. These bolts also extend through the lower part 46, of a circular channeled casting 47, that overlaps the 90 adjacent ends of a platform member 48 (that is preferably provided with side board members 48^A) that forms the fixed platform 95 of the traction engine. And these channel bars also overlap the inner ends of a thin plate 49, that extends out under an angled foot member 50, that is formed on and extends down from the horizontal portion 19, of the upper housing casting 15, and this foot member 50, is also bolted by a rivet bolt 51, to plates 52, that are secured to the bottom of the platform by this rivet bolt 51, which also passes through the platform 48, and thus the plate 49, the platform 48, and the plates 52, are all secured together by the 105 rivet bolt 51, to the foot flange 50, of the housing casting 15; while the plates 46, and the crown plate 43, and the flanged plates 49, are securely bolted and are firmly secured to the channeled casting 47. The 110 horizontal shaft and its supporting and housing casting, with its rolling bearings, together with the crown plate and its outside guard plates, are turned or swung in either direction underneath the stationary 115 platform of the traction engine through an arc of about thirty degrees by a steering mechanism which is not illustrated, as it does not form any part of the present invention.

The shaft 28, is rotated in either direction by the driving shaft 1, and its worm pinion 8, and the worm gear 6, which, being secured to the vertical shaft 1, rotates the shaft 28.

The opposite ends of the shaft 28, may be provided, if desired, with the large round traction wheels with which some traction engines are provided, the rims of which are provided with cogs or blocks; or it may be provided with a worm gear that is 125 130

adapted to be driven by a worm pinion, as shown in the modification illustrated in Figures 2 and 3, or they may be provided with any other kind or character of rotary power transmission elements. For driving the tractor track 61 any usual or preferred sprocket wheels 53 may be used, which may be keyed or otherwise secured upon the shaft 28.

10 Preferably, however, the sprocket wheels are secured to the shaft 28, by a bearing that is composed of a combined round portion 54, and a square portion 55; and the hub 56, of the sprocket wheel is also provided with a combined round and square axial bearing 57, that is formed to fit the round and square bearing portions on the shaft.

20 The ends of the shaft 28 are provided with locking means for preventing the accidental displacement of the sprocket wheels.

25 The locking device may comprise a threaded portion on the opposite ends of the shaft and thread a nut 58, onto the ends 30 of the shaft, that is provided with a split portion that is arranged to be locked to the threads of the shaft by a screw 59. The invention, however, contemplates any means 35 of securing the ground rolling wheels, when they are used, to the shaft; or the track driving sprockets of any other endless track driving members that may be employed to drive the endless ground treading tracks of the traction engines from the shaft 28.

35 The hubs of the casting that surround the shaft 28, have an open space 60, that is closed by a casting that is removably secured to the inner ends of these hubs. This casting 60^A, can be removed at any time to 40 get at the parts of the shafts and their surrounding mechanisms, and also to remove any dirt or oil or grease that may collect in the space around the shaft and in the adjacent inner ends of the hubs of this casting 45 35.

The sprocket wheels support and drive endless ground treading tracks 61, only a fragment of one of which is shown, as they do not form a part of the present invention. 50 A complete view of the endless ground treading tracks that are adapted to be driven by the present driving mechanism for traction engines, can be seen in the Patent No. 1,254,819, issued January 29, 1918, 55 for a traction engine, and in the pending application, Serial No. 374,723, filed April 17, 1920, for ground treading endless traction tracks and their supporting trucks.

55 In Figures 2 and 3, is illustrated a modification of the elements that transmit the rotative motion and power from a vertical shaft 1^A, to the horizontal shaft 28^A. In this modification the vertical shaft is necessarily set and positioned to one side of the 65 horizontal shaft 28^A, instead of directly over

the longitudinal axis of it, as in the preferred construction, and is made long enough to extend below the horizontal shaft, and has formed on its lower end portion a worm pinion 62, the operative center of which is 70 positioned in the right angle, horizontal, or lateral plane of the lengthwise axial center of the shaft 28^A, and on the shaft 28^A, is mounted and secured a worm gear 63, that meshes operatively with the worm pinion 62, 75 of the vertical shaft.

The worm pinion 63, is formed with a hub 64, and pins 65, extend through the hub and through the shaft 28^A, and thereby rigidly secure the pinion 63, to the shaft 28^A. The 80 upper and lower ends of the shaft 1^A, are supported in suitable antifriction bearings 66, which are supported in a housing 67, which encloses the gear and pinion, and the bearings 66, are held in place by collars 68, 85 which are threaded upon the shaft, as shown. The upper end of the shaft is squared as shown at 69, and a coupler 70, fits thereon; and in the upper portion of this coupler is inserted the squared lower end 71, of a shaft 72, 90 upon which is keyed a beveled friction gear 73, which is driven by one or the other of a pair of beveled friction pinions 74 and 75, which are rigidly secured upon a horizontal shaft 76, which is rotatably and slidably mounted 95 in bearings (not shown), supported upon the platform of the tractor, the shaft being shifted by a yoke-shaped lever 77, the depending ends of which are forked, and straddle pins 78, in opposite sides of a 100 slideable but non-rotatable sleeve 79, which is slidably mounted in a fixed hub 80. The outer ends of the sleeve 79, are provided with antifriction bearings 81, which support the shaft 76, within the said sleeve 79. 105 When the pinion 75, is in engagement with the gear 73, the machine moves forward, and when the pinion 74, engages the said gear 73, the machine is reversed. The upper end of the shaft 72, is mounted in an antifriction bearing 82, which is supported in a sleeve 83, which extends through an opening in the hub 80, and also through a slot in the slideable sleeve 79, the sleeve 83, having a flange 84, which is secured to the said 110 hub 80. The lower end portion of the shaft 72, above its squared portion 71, is supported in an antifriction bearing 85, which is supported in the stationary member 86, of a turn table, the other member 87, of said turn 115 table being secured to the deck or platform of the machine, the turn table mechanism being substantially the same as that shown in Figure 1, and hereinbefore described.

The invention comprises a simple, powerful and reliable driving mechanism for traction engines or for any other right angle power transmission device that it can be applied to, and while reference has been made to the preferred construction and arrange- 120 130

ment of the improved driving mechanism, there is no intention to be limited to the construction shown and described, as changes may be made without departing from the 5 invention.

Having described the invention, what is claimed as new and desired to be secured by Letters Patent, is:

1. In a tractor, the combination of a horizontal shaft carrying on its center portion a bevel gear, a vertical shaft, a bevel gear at its lower end in mesh with said bevel gear, a gear mounted near the upper end of the vertical shaft, a shaft carrying a pinion in mesh with the gear, a housing surrounding the vertical shaft and gear mechanism connected therewith and a housing surrounding the horizontal shaft, the second housing having a vertical portion surrounding a part of 10 the first housing and having a sliding fit therewith.
- 15 2. Apparatus according to claim 1 in which the housing surrounding the vertical shaft has a horizontal flange terminating in a bearing flange which has an angular extent of substantially 360° , and means for securing the bearing flange to the frame of the tractor.
- 20 3. Apparatus according to claim 1 in which the housing includes a removable cover

at the end of the vertical shaft and a removable cover below the horizontal shaft substantially in vertical alignment with the vertical shaft.

4. In a tractor, the combination of a horizontal shaft, sprocket wheels rigidly connected thereto at the opposite ends thereof, a bevel gear mounted on the shaft intermediate the sprocket wheels, a vertical shaft having a bevel gear at its lower end in mesh with said bevel gear, a worm gear mounted near the upper end of the vertical shaft, a worm pinion in mesh with the worm gear, a housing surrounding the vertical shaft, the worm gear and pinion, ball bearings 40 between the vertical shaft and its housing, a housing surrounding the horizontal shaft and the bevel gears, said second housing having an upwardly extending portion sliding over the lower portion of the first housing, 45 and a ball bearing between the horizontal shaft and its housing.

5. Apparatus according to claim 4 in which the housing surrounding the horizontal shaft has portions forming bearings for 50 the said sprocket wheels.

In testimony whereof I affix my signature.

Mrs. LINA M. LEYNER,
Administratrix of John George Leyner, deceased.
